INVENTOR:

Selah Hiler
No. 96,111

United States Patent Office.

SELAH HILER, OF NEW YORK, N. Y.

Letters Patent No. 96,111, dated October 26, 1869.

IMPROVED STAIR-ROD.

The Schedule referred to in these Letters Patent and making part of the same.

To all whom it may concern:

Be it known that I, SELAH HILER, of the city, county, and State of New York, have invented a new manufacture, to wit, an Enamelled Stair-Rod; and I do hereby declare that the following is a full, clear, and exact description thereof, reference being had to the accompanying drawings, and the letters of reference marked thereon.

The nature of my invention consists in making stair-rods of thick sheet-iron, bent and fashioned into the ordinary form, as represented by the drawings, and then covering them with a suitable enamel, having a smooth, durable, and brilliant surface, of any color, which may, if desired, be ornamented with gilding or colored in stripes or figures.

To enable others skilled in the art to make and use my invention, I will proceed to describe its method of manufacture.

Stair-rods, of the form represented in my drawings, are usually made of sheet-brass, or some analogous metal. I make mine of sheet or rolled iron, the same being cut from a sheet, and bent into the form shown, by means of suitable rolls and shaping-tools, so as to be capable of being slipped into buttons or holders, fastened on to stairs in the ordinary way; or, if preferred, the rod may be made of a straight strip of thick sheet-iron, having the edges turned over, or

otherwise properly finished, designed to be held in simple loops or staples attached to the stairs.

It is not necessary to give a more particular description of the mode of cutting and fashioning the iron into a stair-rod, as all persons skilled in the art are familiar with it; nor is it necessary to describe the process of enamelling the surface of iron; the art is old and well known, and the ordinary method of enamelling may be employed upon my stair-rod.

When the enamel has been thus fixed on the rod, it is evident that the surface may be ornamented by gilding or painting, in the ordinary manner.

The advantages of my stair enamelled rod consists in its beauty and its cheapness compared with those made of brass, and its not being liable to become tarnished or its lustre impaired by use, never requiring scouring or cleaning.

I do not claim, broadly, the enamelling of the surface of iron, as that is an old art; but

What I do claim as my invention, and desire to secure by Letters Patent, is—

An enamelled stair-rod, as a new manufacture, when made substantially as and for the purpose described.
